United States Patent Office.

JAMES S. BARRY AND ALFRED M. BARRY, OF ALBION, MICHIGAN.

Design No. 4,535, dated December 27, 1870.

DESIGN FOR A FRUIT-GATHERER.

The Schedule referred to in these Letters Patent and making part of the same.

To whom it may concern:

Be it known that we, JAMES S. BARRY and ALFRED M. BARRY, of Albion, in the county of Calhoun and State of Michigan, have invented a new and useful Improvement in Design for Form of Device for Gathering Fruit; and we do declare that the following is a true and accurate description thereof, reference being had to the accompanying photographic illustrations, and being a part of this specification, in which—

Figure 1 is a side, and

Figure 2, a front elevation.

The nature of this invention relates to the peculiar form and shape of the jaws and handles to make a device for gathering fruit from trees.

The invention is fully represented in the accompanying photographic illustrations, where the device is shown in two different positions.

What we claim as our invention, and desire to secure by Letters Patent, is—

The design for a device for gathering fruit from trees, as shown.

JAMES S. BARRY.
ALFRED M. BARRY.
